FRANK MACEY, OF MILWAUKEE, WISCONSIN.

ANTIFRICTION TIP FOR FURNITURE.

Application filed March 9, 1922. Serial No. 542,336.

The invention relates to anti-friction tips for furniture.

One object of the invention is to provide an anti-friction tip adapted to be applied to the legs of pieces of furniture without danger of splitting the legs, and which includes a metal head having a small surface contact with the floor so that the piece of furniture may be readily moved by sliding it over the floor, the contacting face of the head being curved to prevent injury to the floor.

A further object of the invention is to provide an anti-friction tip for furniture in which the head is separate from the attaching member and to connect this member, such as a brad, to the head in such a manner that the tip may be driven into the leg of a piece of furniture by blows delivered to the head without danger of separating its parts, and so that the tip may be removed from the leg without danger of separating its parts.

With the above and other objects in view the invention consists in the furniture tip hereinafter described and all equivalents.

In the drawings: Fig. 1 is a section taken on the line 1—1 of Fig. 2; Fig. 2 is a plan view of a tip embodying the invention; Fig. 3 is a view of the parts making up the tip prior to their connection; Fig. 4 is a view similar to Fig. 1 showing a slightly modified form of head construction for the tip; Fig. 5 is a perspective view of the tip shown in Fig. 4; Fig. 6 is a view similar to Fig. 1 showing a slightly modified form of head construction for the tip.

The tip comprises a head or floor-engaging member 6 and an attaching member 7.

In each form the head member 6 is of pressed metal formed into a cylindrical cup having an annularly extending convex floor-engaging portion 8 merging at its outer edge into an annular cylindrical flange 9 and at its inner edge into a conical portion 10, the section of smallest diameter of said conical portion merging into a ring portion 11 having its opening 12 centered in the head. In addition to the above named parts of the head member 6, the flange 9 may have short spurs 13 formed thereon, as shown in Figs. 4 and 5, or the edge may be formed to provide an annular cutting part 21, as shown in Fig. 6.

The attaching member 7 preferably consists of a brad having a pointed end 14 and

a tapered end 15 with a flange 16 adjacent said tapered end forming a head-engaging shoulder 17. With this construction the tapered end 15 is forced or driven into the opening 12 and is then upset or riveted to the head member 6 to form a head 18 which is located within the depression formed by the conical portion 10. By this construction brad 7 has a drive fit on the head and the head 6 is tightly riveted between the shoulder 17 and the shoulder 19 formed by head 18. With this connection the tip may be driven into or taken out of the leg of a piece of furniture without danger of separating the parts, as the pressures exerted upon the head member in driving are transmitted to the brad through the shoulder 17 and the pressures exerted in extracting the tip are resisted by the flanged head 18. The tip may be set or driven into the furniture by striking the curved annulus 8 with a hammer or other suitable tool and the tip may be so driven as to embed its flange 9 in the leg 20 to which it is attached, as shown in Fig. 1. However, to positively relieve the brad of any shearing strains occasioned by striking the tip against an obstacle when moving the piece of furniture to which it is attached, the short spurs 13 may be used, or the edge provided with the part 21 to relieve the brad of shearing strains. As the tip has but one attaching member and this is located at the center there is no danger of splitting the leg to which the tip is attached as there is ample stock from the center to the outer edge of the leg. With such a construction the limited contact afforded by the annulus 8 with the floor reduces the frictional engagement between the legs of the piece of furniture and the floor to a minimum so that the article may be readily shifted about with a minimum of effort.

It will be further noted that by the use of a suitable nail set applied to the central depressed portion of the tip that it may be driven into the furniture without the danger of flattening the curved floor-engaging portion 8 of the tip by repeated blows of a hammer.

What I claim as my invention is:

1. In an anti-friction tip for furniture, the combination of a cup-shaped floor-engaging member having a recessed central portion and an annular floor-engaging portion, and a brad having spaced cooperative

flanges on its head end fixedly clamping it to said recessed central portion out of contact with the floor.

2. In an anti-friction tip for furniture, 5 the combination of a floor-engaging member having a convexly curved annulus engageable with the floor and an annular flange portion engageable with the article to which the tip is applied, there being a conically 10 formed central recess within said annulus, and fastening means passing through the central portion of the floor-engaging member and having its head disposed in said recess out of contact with the floor.
3. In an anti-friction tip for furniture, 15 the combination of a cup-shaped floor-engaging member having a recessed central portion and an annular floor-engaging portion, and a brad having its head disposed in said

recess free of the floor and flanged to engage 20 one side of said member and having a co-operative flange engaging the other side of said member.

4. In an anti-friction tip for furniture, 25 the combination of a floor-engaging member having a recessed central portion and an annular floor-engaging portion, and a brad having a tapered head and a flange adjacent thereto, said tapered head having a pressed fit in a central opening in said central portion and having a part upset against said member to form a flanged head, said flanged head being disposed in said recessed portion 30 free of the floor.

In testimony whereof, I affix my signature.

FRANK MACEY.
